ANNEALING SPIDER FOR SUPPORTING COILS
OF WIRE OR THE LIKE

James L. Whitten, Fairview Park, Ohio, assignor to
The Alloy Engineering Company

Continuation of design application Ser. No. D-78,191,
Jan. 14, 1964. This application Apr. 22, 1965, Ser. No.
85,126

Term of patent 14 years

(Cl. D41—1)

Fig. 2

Fig. 1

Fig. 3

FIGURE 1 is a side elevational view of an annealing spider for supporting coils of wire or the like, showing my new design;

FIGURE 2 is a top plane view thereof; and

FIGURE 3 is a side elevational view thereof, in reduced scale and rotated at 180° from the position shown in FIGURE 1.

This is a continuation of design application Serial Number D. 78,191, filed January 14, 1964 and now abandoned.

I claim:

The ornamental design for an annealing spider for supporting coils of wire or the like, as shown.
